(57) **CLAIM**

(21) Appl. No.: **29/299,019**

The ornamental design for a large-surface measuring device
with adjustable position markers, as shown and described.

(22) Filed: **Dec. 18, 2007**

DESCRIPTION

(51) **LOC (8) Cl.** **10-04**

FIG. 1 is a fragmented perspective elevational view of a
large-surface measuring device with adjustable position
markers showing my new design;

(52) **U.S. Cl.** **D10/71**

FIG. 2 is a fragmented front elevational view of a large-
surface measuring device with adjustable position markers;
and,
